PARING ATTACHMENT

Floyd J. Polasik, Woodstock, Ill., assignor of one-half to Otto Reitz, Chicago, Ill.

Application November 26, 1943, Serial No. 511,784

6 Claims.

(Cl. 30—284)

This invention appertains to attachments or accessories which can be readily secured to a knife or similar cutting instrument for the purpose of adapting the said cutting instrument to facilitate the operations of paring, or peeling, as well as slicing therewith.

One object of my invention is to provide an accessory of the aforementioned character which is made of one piece of material and which is readily attached to the blade of a cutting instrument.

Another object of my invention is to provide an article of the aforementioned character which has an offset forward guide portion which pilots the cutting edge of a knife and facilitates the peeling action.

Another object of my invention is to provide an improved and slightly modified form of the form mentioned in the preceding paragraph wherein a rearward guide portion is also provided in order to definitely align the edge of the cutting instrument for paring purposes.

Another object of my invention is to provide an article for the purpose of paring, peeling, or slicing, which is made up of two sections, namely a tubular section and a wire section telescoped therein in order to provide adjustability adapting the accessory as a paring or peeling attachment so as to be attachable to blades of varied widths of cutting instruments.

Another object of my invention is to provide a peeling or paring or slicing attachment for the blades of cutting instruments which is practical and efficient in its operation, as well as useful for cutting, slicing, or paring and which is of such simple elemental structure as to permit manufacture economically in quantity production.

Other objects and advantages resident and inherent in my invention will become apparent from an examination of the accompanying drawings, and the elucidation in the ensuing description, wherein like symbols are used to designate like parts, and in which;

Fig. 1 is a perspective view showing one form of my attachment or accessory as it is secured to the blade of a cutting instrument shown in the operation of peeling a potato.

Fig. 2 is a cross-sectional view looking in the direction of the plane passing thru line 2—2 of Figure 1.

Fig. 3 is a perspective view of the attachment per se.

Fig. 4 is a rear view of a cutting instrument showing my invention, the paring or peeling accessory, attached thereto.

Fig. 5 shows a perspective view of a slightly modified form of my invention as secured to the blade of a cutting instrument.

Fig. 6 shows a cross-sectional view on the line 6—6 of Figure 5.

Fig. 7 shows a perspective view of still another slightly modified form of my invention as secured to the blade of a cutting instrument.

Fig. 8 is an enlarged cross-sectional view taken on the line 8—8 of Figure 7.

Fig. 9 is a perspective and exploded view of the two elements comprising the modified form indicated in Figures 7 and 8, showing how adjustability is obtainable thru the use of this form of my invention.

Referring to the various views shown on the drawings submitted herewith, the form illustrated in Figures 1, 2, 3 and 4 is, generally, designated 11 and is secured to a cutting instrument generally designated 10, the cutting instrument being a knife, having a handle 15, a blade 16 with a cutting edge 22 to which my invention is slidably and removably attached. The instrument is shown peeling a potato 12, having usual eyes 13, and it is to be stressed that the attachment in no way impairs the operation of the cutting blade, especially, leaving free the point 24 of the blade 16 for removing the eyes after the rind 14 has been completely removed from the potato 12.

The structure of this form of my invention is more or less C shaped comprising a base portion 17, and two leg portions 18, which terminate in U shaped clamping portions 19 having the ends 20 curved outwardly, slightly, so as to provide a suitable clamping throat to receive the blade 16 and to permit easy entry of the rear portion of the blade 16 when the device is to be attached to the said blade of a cutting instrument.

I wish to, particularly, point out that the portion 17 is slightly offset upwardly as indicated by the minute radius 21 in order to provide a space 23 between the cutting edge 22 and the guide or resting portion 17 of the cutting or paring attachment, and thus to furnish a good guide, over the surface of the product being peeled, for the knife blade during the paring operation.

The cutting instrument is usually held by the handle 15 and the peeling operation is performed as it would ordinarily be performed if my attachment were not secured thereto. My attachment by virtue of the portion 17 and its location with relation to the cutting edge 22 of the blade 16 as heretofore elucidated, furnishes a suitable guide and prevents from cutting too thick a rind or peel from the potato or other vegetables or fruit which it may be desired to peel.

In Figures 5 and 6, I show a modified form of my invention generally designated 25 which is similar in structure to the form shown in Figures 1, 2, 3 and 4 with the exception that it is provided with additional guiding means.

The structure primarily includes a C shaped portion comprised of a base portion 26 and two upright leg portions 27; the portion 26 being offset slightly from the portions 27 by virtue of the slight curvature 32 which offsets the said portion 26, the uprights 27 terminating in U shaped throat portions 28 and because of the outwardly curved ends 29 will facilitate inserting the back of the blade 16 of a cutting instrument. However, in this instance, the two end portions 29 are interconnected by another portion 30 which furnishes a back rest or guide definitely positioning the knife in a certain relationship with respect to the contour of the vegetable or fruit to be peeled 12, and thus the rind 14 is allowed to glide thru the opening or space 31, in between the cutting edge 22, and the rest portion 26. It can readily be seen that with this type of construction the portion 31 greatly aids in maintaining the cutting edges in proper alignment so as to prevent cutting too thick a peel from the article to be derinded.

In Figures 7, 8, and 9, the structure is similar to that of Figures 5 and 6 with the exception that the structure generally identified 33 is resolved into two elements 34 and 35, namely, a lower C shaped portion, and an upper portion which is made of tubular material; the lower portion is provided with a forward guide or base 40, terminating in two legs 41 which are telescopically fitted into the legs 37 of the upper element terminating in a U shaped throat portion 38 and by virtue of the bent portions 43 offers a readily accessible throat portion for the back of the knife blade 16 so as to permit inserting the same easily and without any difficulty. The portions 43 being further bent at 39 so as to form a connecting rear base or guide portion 36. The forward base portion or guide 40 is offset with respect to the cutting edge 22 by the slight radial bend 42 so as to furnish the opening 44 thru which the pared material or rind will move after paring, and is similar to the slight offset indicated for the other forms as heretofore elucidated and described.

The principal difference between this form and the one shown in Figures 5 and 6 is that it is made up of two sections telescopically fitted so as to accommodate different widths of cutting blades of paring instruments which may vary in accordance with standards of manufacture in commercial production.

In order to adapt my attachment or accessory for slicing purposes, it is to be noted that the wire section of my invention can be made of a rather tenacious and springy material which will allow a certain degree of flexibility in the legs 18 of the first form indicated, the legs 27 of the second form, and the telescopic legs 37 of the third form.

In applying a slight pressure when gripping the handle 15 thus tending to flex the guiding portions of the various forms of my invention namely, the portions 17, 28, or 40, the gaps 23, 31 and 44 may be so enlarged or varied as to permit slicing and thus give fairly regular and even cuts.

Altho I have herein indicated several forms of my invention, at the same time disclosing and revealing the nature, operation and construction thereof, yet it is believed that my invention is susceptible of various modifications, alterations, and improvements, therefore, I reserve the right to all such modifications, alterations, and improvements, which come within the scope and

spirit of my invention, within the purview of the foregoing description, as well as within the embodiments indicated in the accompanying drawings; my invention to be limited only by the subjoined claims.

Having thus disclosed and revealed my invention, what I claim as novel and desire to secure by Letters Patent is:

1. An attachment of the character described comprising, two sections, a forward C shaped section, and a rearward C shaped section of lesser width than the said forward C shaped section, the said two sections being interconnected by U shaped portions.

2. An attachment of the character described comprising, two C shaped sections each consisting of a base portion and leg portions extending from the termini of said base portion, the leg portions of each of said C shaped portions interconnected by U shaped portions, the base portions of each of said C shaped portions lying without imaginary geometric planes embracing the leg portions of the said C shaped portions respectively.

3. An attachment of the character described comprising, two C shaped sections each consisting of a base portion and leg portions extending from the termini of said base portion, the leg portions of each of said C shaped portions interconnected by U shaped portions, the base portions of each of said C shaped portions lying without imaginary geometric planes embracing the leg portions of said C shaped portions respectively, the said C shaped portions being of unequal width.

4. An accessory of the character described comprising a C shaped tubular element including a base portion, leg portions extending from the termini of said base portion, and telescopic leg portions interconnected to said leg portions by U shaped portions; and a C shaped element including a base portion, and two leg portions extending from the termini of said base portion, the leg portions of the said C shaped element being slidably and adjustably secured to the telescopic leg portions of the said C shaped tubular element.

5. An accessory of the character described comprising, a C shaped tubular element including a base portion, leg portions extending from the termini of said base portion, and telescopic leg portions interconnected to said leg portion by U shaped portions; and a C shaped element including a base portion, and two leg portions extending from the termini of said base portion, the leg portions of the said C shaped element being slidably and adjustably secured to the telescopic leg portions of the said C shaped tubular element, the said C shaped element and the said C shaped tubular element being of unequal width.

6. An attachment of the character described comprising, a C shaped element including a base portion, leg portions extending from the termini of said base portion, the said leg portions terminating in U shaped throat portions adapted to be secured to the rear edge of a cutting instrument, the inner portions of the said throat portions contacting the rear edge of the said cutting instrument, whereas the cutting edge of the said cutting instrument is maintained free from contact with the said base portion, the said base portion being offset from said leg portions to create a gap with respect to the cutting edge of the said cutting instrument.

FLOYD J. POLASIK.
